MINING CAR BUMPER COUPLING

Willie L. Brock and Walter F. Jones, Bandy, Va.

Application August 29, 1940, Serial No. 354,756

1 Claim. (Cl. 213—64)

This invention relates to an improved coupling especially adapted for use on mining cars and aims particularly to provide a coupling by means of which one car may be drawn by another car or by means of which one of the cars may be pushed by the other with the coupling elements forming abutments or bumpers.

Still another aim of the invention is to provide a coupling wherein the coupling elements are yieldably connected to the cars to form either a yieldable draft connection or a yieldable abutment.

More particularly, it is an aim of the invention to provide a coupling having novel means for automatically coupling the cars to thereby eliminate the need for manually completing the coupling and the danger incidental to the worker in being disposed between the cars as they are being moved together.

Other objects and advantages of the invention will hereinafter become more fully apparent from the following description of the drawings, which illustrate a preferred embodiment thereof, and wherein:

Figure 1 is a side elevational view showing the coupling in a coupled position.

Figure 2 is a top plan view of the same.

Figure 3 is an enlarged longitudinal vertical sectional view taken substantially along the plane of the line 3—3 of Figure 2.

Figure 4 is a longitudinal horizontal sectional view of the coupling taken substantially along the plane indicated by the line 4—4 of Figure 3.

Figure 5 is a transverse vertical sectional view of the coupling taken substantially along the plane indicated by the line 5—5 of Figure 3.

Figure 6 is a fragmentary side elevational view of a portion of one of the coupling blocks,

Figure 7 is a sectional view taken substantially along the plane of the line 7—7 of Figure 6.

Figure 8 is a plan view showing a plate used for attaching one of the coupling members to a car, and

Figure 9 is a sectional view taken substantially along the plane of the line 9—9 of Figure 1.

Referring more particularly to the drawings, wherein like reference characters designate like or corresponding parts throughout the different views, 10 designates portions of adjacent ends of a pair of mining cars provided with depending flanges or aprons 11 having openings 12, and 13 designates generally the coupling, comprising

the invention, and which is adapted to connect the two cars 10.

The coupling 13 includes a pair of coupling blocks 14 and 15 each of which is provided with a drawbar extending from the rear end thereof. The drawbar 16 of the block 14 is slidably mounted in an opening 17 of a plate 18 which is attached to the outer side of one of the flanges 11 over its opening 12 by means of a plurality of fastenings 19. The drawbar 16 therefore extends not only through the opening 17 but also through the opening 12 of the flange 11 to which the plate 18 is attached. An expansion coil spring 20 is mounted on the drawbar 16 and has one end abutting against the inner side of the plate 18 and its opposite end abutting against a washer 21 which is mounted on the drawbar 16 and retained in position thereon by means of a pin 22. The pin 22, as best seen in Figure 3, is in the form or shape of an inverted L with the longer end thereof extending through an opening 23 in the drawbar 16. A cotter pin 24 extends through the longer end of the pin 22 for retaining said end in engagement with the opening 23. As best seen in Figure 8, the plate 18 is provided with a pair of indentations 25 to receive pins 26 which project from the back side of the block 14 to retain said block in substantially a horizontal position.

The block 14 is provided with an arcuately shaped recess 27 which opens outwardly of its forward end and in which is disposed one end of a link 28. A pin 29 extends perpendicularly through the block 14 and through the recess 27 and link 28 to connect said link 28 to the block 14. A cotter pin 30, which extends through the lower end of the pin 29, prevents accidental removal of said pin.

The drawbar 31 of the block 15 is slidably mounted in an opening 32 of a plate 33 and is similarly connected by fastenings 19 to the flange 11 of the other car 10 and over its opening 12. The drawbar 31 also extends through an opening, not shown, in a hanger 34. A pin 35 extends through and is mounted in the drawbar 31 behind the plate 33 to limit the outward movement of the block 15 relatively to plate 33. A coil spring 36, of the expansion type, is disposed with one end abutting against the pin 35 and its opposite end abutting against the hanger 34 for yieldably urging the drawbar 31 outwardly. A second pin 37 may be mounted in the drawbar 31 behind the hanger 34, as illustrated in Figures 1 and 2. The drawbar 31 is

preferably so mounted that it will not turn relatively to the plate 33 and the hanger 34 in which it is slidably disposed to retain the block 15 substantially in a horizontal position.

Blocks 14 and 15 diverge toward their outer, forward ends and the block 15 is provided with a recess 38 which diverges toward and opens outwardly of the forward end thereof for receiving the free end of the link 28 and for guiding said end toward the restricted portion of the recess 38. Recess 38 is provided with an elongated restricted portion at its inner end, designated 39, for receiving a slide 40 which is slidably mounted therein and which is provided with the enlarged head 41 which projects toward and extends into the enlarged portion of the recess 38. The slide 40 is also provided with a perpendicularly disposed elongated opening 42, for a purpose which will hereinafter become apparent. The block 15 is provided with aligned openings 43 in its top and bottom portions which open into the recess 38 and in which is adapted to be disposed the ends of a pin 44 the intermediate portion of which extends perpendicularly through the recess 38. The block 15 is also provided with a perpendicular slot 45 which is disposed longitudinally thereof and which intersects with the recess portion 39. A trigger 46, as best seen in Figure 9, is mounted on and keyed to the square intermediate portion of a pin 47 which is journaled in the block 15 and which extends through the slot 45 above the slide 40. A crank 48 is formed integral with one end of the pin 47 and is disposed on one side of the restricted rear end 49 of the block 15. The opposite end of the pin 47 extends beyond the opposite side of the restricted end 49 and is squared to receive a portion of a spring latch member 50 which is keyed thereto and which is provided adjacent its free end with an inwardly extending rounded projection 51 which, as best seen in Figures 6 and 7, is adapted to engage one or the other of two spaced indentations 52 in the last mentioned side of the portion 49, for a purpose which will hereinafter become apparent.

One end of the trigger 46 extends downwardly of the slot 45 and through the opening 42 of slide 40. The opposite end of the trigger 46 extends outwardly of the slot 45 and forwardly of the block 15 and is connected by means of a link 53 to the upper end of the pin 44.

From the foregoing it will be obvious that the two cars 10 when coupled as illustrated in Figures 1 to 4 by means of the coupling 13, will be yieldably connected so that either of the cars may be drawn by the other and when the coupling is thus employed for draft means the spring 20 will provide yieldable means to permit the block 14 to be resiliently drawn away from the plate 18 to take up sudden jerks which would otherwise be imparted to the cars 10. The blocks 14 and 15 are also adapted to abut to form a bumper between the cars 10 so that either of the cars may be pushed by the other and when the coupling 13 is thus employed the spring 36 will provide resilient means to permit the block 15 to yieldably move toward the plate 33 to similarly take up sudden shocks and jerks. It will be noted that the spring 36 normally holds the drawbar 31 and the block 15 in an extended position relatively to the plate 33, as illustrated in Figures 1 to 4, to permit said parts to move toward the plate 33 which will thereby compress the spring 36. The link 28 is of such

a length that it will not quite contact the head 41 when the slide 40 is in a retracted position and when the blocks 14 and 15 are abutting. Obviously, when one of the cars is being drawn by the other car the blocks 14 and 15 will move out of abutting engagement and the free end of the link 28 will engage against the pin 44. To uncouple the cars 10, the crank 48 is swung forwardly of the block 15 to swing the upper end 10 of the trigger 46 upwardly and rearwardly to raise the pin 44 above the link 28 to thereby release the link. At the same time, the lower end 15 of the trigger 46 will be swung forwardly to move the slide 40 to a forward, projected position. This movement of the crank 48 will cause the latch 50 to swing in a counterclockwise direction, from its position, as seen in Figure 6, to cause its projection 51 to move into engagement with the forward, exposed recess 52 to thereby latch the trigger 46 in a retracted position to hold the pin 44 in a retracted position and the slide 40 in a projected position. To recouple the cars 10 the blocks 14 and 15 are moved toward one another causing the link 28 20 to enter the recess 38 and be guided by its inwardly converging side walls into engagement with the head 41. The impact of the free end of the link 28 with the head 41 will drive the slide 40 to a retracted position to thereby swing the trigger 46 back to its position, as seen in Figure 3, to move the pin 44 downwardly and into a projected position with its lower end in engagement with the lower opening 43. The pin 44 will pass through the link 28 to thereby automatically couple the blocks 14 and 15. This will likewise cause the latch member 50 to return to its position, as seen in Figure 6, with the projection 51 engaging the recess 52, as illustrated in Figure 7, to retain the trigger 46 and the pin 44 in projected positions.

The tits 26 will normally engage the recesses 25 in the plate 18 to hold the block 14 in substantially a horizontal position corresponding to the position of the block 15. In order to enable either of the cars 10 to be dumped by means of a conventional cradle dump, not shown, the drawbar 16 is mounted to swivel in the opening 17 so that the block 14 may be turned relatively to the plate 18 to permit either of the cars 10 to be rocked in either direction for dumping. The spring 20 will be compressed slightly in this operation to permit the tits 26 to ride out of the recesses 25 so that the block 14 may be rotated relatively to the plate 18 to accommodate the rocking, dumping movement of one or the other of the cars 10. When the car 10 which is dumped is returned to its normal, upright position the block 14 will be swung back to its original position and the spring 20 will retract 50 the block 14 to cause the tits 26 to again engage the recesses 25 to hold the block 14 in substantially a horizontal position.

Various modifications and changes are contemplated and may obviously be resorted to as 65 only a preferred embodiment of the invention has been disclosed.

We claim as our invention:

A drawbar mounting comprising a block, a drawbar extending therefrom and adapted to be slidably and swivelly connected to an end of a mining car, spring means for yieldably urging the drawbar and block toward the car, a plate adapted to be attached to said end of the car and through which the drawbar extends and in which it is slidably and swivelly mounted, said

plate being provided with horizontally spaced indentations in its outer side, said block being yieldably held by the spring means in engagement with the plate, and said block having projections arranged to seat in the indentations, when the block is in a horizontal position, to releasably retain the block thus positioned, and

5 said spring means permitting the block to yield away from the plate to allow the projections to ride out of the indentations when the block is turned relatively to the plate.
